GOLF BALL RETRIEVER

James R. Steinle, Greenville, Ohio

Application January 18, 1957, Serial No. 44,526

Term of patent 14 years

(Cl. D34—5)

I claim:

The ornamental design for a golf ball retriever, as shown.
